(57) **CLAIM**

The ornamental design for an occlusion training band with buckle, as shown and described.

DESCRIPTION

FIG. 1 is a top front perspective view of an occlusion training band with buckle showing my new design;

FIG. 2 is a front elevation view thereof;

FIG. 3 is a right side elevation view thereof;

FIG. 4 is a left side elevation view thereof;

FIG. 5 is a top plan view thereof; and,

FIG. 6 is a bottom plan view thereof.

1 Claim, 2 Drawing Sheets
